UNITED STATES PATENT OFFICE

HERMAN C. REICHARDT, OF EVANSTON, ILLINOIS, ASSIGNOR, BY DIRECT AND MESNE ASSIGNMENTS, TO STAR-BRITE CORPORATION, OF CHICAGO, ILLINOIS, A CORPORATION OF ILLINOIS

DESIGN FOR A COMBINED CASING OR FRAME AND BRACKET FOR LIGHT REFLECTOR SIGNAL

Application filed December 31, 1926. Serial No. 42,328. Term of patent 14 years.

To all whom it may concern:

Be it known that I, HERMAN C. REICHARDT, a citizen of the United States, residing in the city of Evanston, in the county of Cook and State of Illinois, have invented a new, original, and ornamental Design for Combined Casing or Frame and Bracket for Light Reflector Signal, of which the following is the specification, reference being had to the accompanying drawing, forming part thereof.

Figure 1 is a front elevation of combined casing or frame and bracket for light reflector signal.

Figure 2 is a rear view of the parts shown in Figure 1.

Figure 3 is a side view of the same.

I claim:

The ornamental design for a combined casing or frame and bracket for light reflector signal, as shown.

HERMAN C. REICHARDT.
